(57) **CLAIM**

The ornamental design for a case for cigarette rolling paper, as shown and described.

DESCRIPTION

1. Case for cigarette rolling paper

1.1 : Perspective

1.2 : Left

1.3 : Right

1.4 : Back

1.5 : Top

1.6 : Front

Cigarette rolling papers case with a built in sealable rolling tray; **1.1**: perspective view—displays case fully assembled with sealed rolling tray; **1.2**: left view—displays side angle of case fully assembled with sealed tray; **1.3**: right view—displays side angle of case fully assembled with sealed tray; **1.4**: back view—displays back angle of case fully assembled with sealed tray; **1.5**: top view—displays top view of case

(Continued)

fully assembled with sealed tray; **1.6**: front view—displays front angle of case fully assembled with sealed tray;
